UNITED STATES PATENT OFFICE.

WARD Z. FLOWER, OF GIBBON, MINNESOTA.

SPARK-PLUG.

988,451.

Specification of Letters Patent. Patented Apr. 4, 1911.

Application filed May 31, 1910. Serial No. 564,234.

To all whom it may concern:

Be it known that I, WARD Z. FLOWER, a citizen of the United States, residing at Gibbon, in the county of Sibley and State 5 of Minnesota, have invented certain new and useful Improvements in Spark-Plugs: and I do declare the following to be a full, clear, and exact description of the invention, such as will enable others skilled in the art 10 to which it appertains to make and use the same.

This invention relates to improvements in spark plugs of the jump-spark type, the primary object of the invention being to 15 provide means whereby the electrodes will be automatically kept bright and clean and free from the coking deposit which now ordinarily accumulates on the electrodes in combustion engines and prevents sparking 20 so as to seriously interfere with the successful operation of the engine.

Another object of the invention is to provide a spark plug having one of its electrodes adjustable to compensate for wear.

With the stated objects, and other incidental objects, in view, the invention consists in certain novel features of the device illustrated in the accompanying drawings, all of which will be hereinafter first fully 30 described and then more particularly pointed out in the appended claims.

In the accompanying drawings, Figure 1 is an elevation of my improved spark plug showing it applied to an engine. Fig. 2 is 35 an enlarged longitudinal section of the plug. Fig. 3 is a transverse section on the line 3—3 of Fig. 2. Fig. 4 is a similar view on the line 4—4 of Fig. 2, and Fig. 5 is a similar view on the line 5—5 of Fig. 2.

In carrying out my invention, I provide 40 an outer tubular casing or socket member 1, having a threaded inner end adapted to be engaged in a threaded opening in the wall of the engine cylinder so as to bring the inner end of the spark plug within the combustion chamber of the engine. The socket member is also provided with an angular portion 2 to be engaged by a wrench or other tool in securing the plug in position 45 and beyond this angular portion the extremity 3 of the member is threaded, as shown. On the inner end of the socket member is formed a substantially U-shaped bracket 4, in the shoulder of which is a 50 threaded aperture adapted to receive the inner or stationary electrode 5, the said

bracket being disposed entirely within the combustion chamber of the engine as clearly shown in Fig. 1. The electrode 5 is provided with a threaded stem or shank 6 which is engaged in the threaded aperture in the bracket 4 and is thus secured in the socket member in such a manner that it may be readily adjusted to compensate for the wear of either electrode. On the threaded 65 stem of the fixed electrode is mounted a jam nut 7 which is adapted to be turned home against the end of the socket member to secure the electrode in its adjusted position, while in the outer end of the stem is preferably arranged a cotter pin or other stop 8 to prevent the nut 7 from being unintentionally removed from the shank. In the head or outer end of the fixed electrode is a 70 conical recess 9 to be engaged by the end of the movable electrode in the operation of the device.

In the outer end of the socket member 1 is formed a socket 10 which receives the insulating sleeve or lining 11, said lining entering the bore of the socket member and having an annular enlargement 12 formed on its outer surface substantially midway its ends which fits snugly within the socket. Between the inner end of the enlargement 12 and the inner end of the socket 10 is arranged a suitable packing 13 to prevent leakage of gases between the lining and the member 1 of the plug. The outer end of the lining 11 projects beyond the outer end 90 of the socket member 1 and through the locking nut or gland 14 which is screwed onto the threaded outer end 3 to secure the sleeve or lining firmly in place, a suitable packing 15 being arranged between the end 95 14 and the enlargement 12 as shown.

Arranged against the outer end of the insulating sleeve 11 is an outer member 16 having on its inner end a reduced tubular extension or stem 17 which is exteriorly 100 threaded and projects through the sleeve or lining 11 and has mounted on its inner extremity a fastening nut 18 adapted to be turned home against the sleeve or lining to clamp the same firmly on the outer plug member, the bore of the lining 11 being enlarged at an intermediate point of its length to accommodate the nut 18 as shown in Fig. 2, and as will be readily understood. The outer plug member 16 is of a cylindrical 110 formation and its outer extremity is closed by a threaded plug 19 having in its inner

end a conical recess 20 which forms the outer end wall of the member 16 and furnishes a seat for the electrode piston. On the outer end of the plug 19 is formed a threaded extension 21, said plug and extension being centrally bored, as shown at 22. On the extension 21 is mounted a binding nut 23 by means of which one of the current conductors is secured to the plug. The outer end of the cylindrical plug member 16 is hollow, as shown most clearly in Fig. 2, to provide a chamber communicating with the bore of the stem 17, the inner end of said chamber being conical to form a seat corresponding to the seat presented by the inner end of the plug 19. Slidably mounted in the said chamber is a piston 24, the opposite ends of which are conical to engage the conical seats at the opposite ends of the chamber, while from the inner end of the piston a connecting rod or stem 25 extends through the stem 18 and has an electrode 26 on its inner extremity, said electrode being thus supported in position to engage the conical depression or recess 9 in the stationary electrode 5.

When the electrodes are separated, as shown in Fig. 2, the closing of the circuit by the timer or interrupter, usually employed on explosive engines, will cause a spark to be produced between the electrodes. The several parts will, of course, be so adjusted as to create the spark at the moment of greatest combustion within the engine cylinder. When the gas within the engine cylinder has been compressed, the pressure will act on the piston 24 to force the same outward and separate the electrodes so that a spark may be produced and an explosion effected. When the engine piston moves in the opposite direction to discharge the spent gas, a partial vacuum is produced so that the atmosphere pressure on the piston 24 through the bore 22 of the plug 20 will drive the piston inward so that the electrode 26 will be carried forcibly against the fixed electrode, the contact between the two electrodes causing any soot or other product deposited thereon to be dislodged. A polishing action will also take place between the electrodes so that they will be kept bright, and coking or corroding of the same cannot occur. The piston 24 fits sufficiently snug in the outer plug member to prevent escape of gas or entrance of air therethrough, the air admitted through the plug 19 acting as a cushion to prevent jarring of the piston on its outer movement and consequent bending or breaking of the stem 25. By securing the electrode 5 in the manner shown and described, any wear of either electrode may

be immediately taken up and the parts adjusted to proper operating relation.

Having thus described my invention, what I claim is:—

1. A spark plug comprising a socket member, a stationary electrode arranged at the inner end thereof, an insulation lining in said member, a cylindrical outer member extending through said lining, a piston operatively mounted in said member, and an electrode carried by the inner end of said piston and adapted to be moved thereby into and out of engagement with the stationary electrode. 75

2. A spark plug comprising a socket member, an insulating lining therein, a stationary electrode adjustably secured in the inner end of the socket member, a cylindrical outer member in the outer end of said lining communicating at its outer end with the atmosphere and at its inner end with the combustion chamber of the engine, a piston slidably mounted in the outer end of said member, and an electrode carried by said piston 80 and adapted to be operated thereby to impinge against the stationary electrode. 85

3. A spark plug comprising a socket member adapted to be secured in the combustion chamber of an engine, a bracket on the inner end of said member, a stationary electrode having a threaded engagement in said bracket, a jam nut mounted on said electrode to bear against said bracket, an insulation lining arranged in said member, an outer 90 member secured in said lining, a piston slidably mounted in said outer member, and an electrode carried by said piston and adapted to be operated thereby to impinge against the stationary electrode. 95

4. A spark plug comprising a socket member adapted to be secured in the combustion chamber of an engine, a stationary electrode secured in and housed by the inner end of said casing, a tubular insulation lining arranged in the outer portion of said member, an outer member having a tubular stem secured in said lining, a tubular plug adapted to close the outer end of said member, a piston slidably mounted in said member, a stem or rod extending from said piston through the tubular stem of said outer member, and an electrode arranged on the inner end of said stem and adapted to be moved forcibly against the stationary electrode. 105 110 115

In testimony whereof I have hereunto set my hand in presence of two subscribing witnesses.

WARD Z. FLOWER.
